(No Model.)

T. A. MACAULAY.

SEWING MACHINE.

No. 276,842.

Patented May 1, 1883.

UNITED STATES PATENT OFFICE.

THOMAS A. MACAULAY, OF NEW YORK, N. Y.

SEWING-MACHINE.

SPECIFICATION forming part of Letters Patent No. 276,842, dated May 1, 1883.

Application filed January 13, 1883. (No model.)

To all whom it may concern:

Be it known that I, THOMAS A. MACAULAY, of the city, county, and State of New York, have invented certain new and useful Improvements in Sewing-Machines, of which the following, with the accompanying drawings, is a specification.

Similar letters refer to like parts in the different figures.

10 My invention relates to improvements in devices for operating feed and shuttle mechanism, which will be hereinafter more fully described.

15 In the drawings, Figure 1 is a sectional rear end view of a sewing-machine embodying my invention. Fig. 2 is a central side view, partly in section, of the same. Fig. 3 is a bottom view of the front end of the bed, showing part of the feed mechanism, to which some of 20 my improvements relate.

A A is the rear part of the hollow arm. A² is the main needle-driving shaft. B' B² are eccentrics on the main shaft. C is a pitman. D D' is a pitman-lever. E is a bell-crank lever. F is a stud. G is a shuttle-carrying lever. g is a pin connecting the pitman C to the bell-crank lever, and serving as a fulcrum for the slotted pitman-lever D D'. H is a shuttle-lever stud. J is a ball-joint. J' is a projection 30 from the bed, in which J operates. K is a main feed-lever. K' is the short arm of the same. L is a secondary feed-lever. M is a ball on the end of the long arm of the bell-crank lever E. N is a ball on rear end of the main feed-lever K. n is a stud-pin connecting the feed-regulating lever R with the feed-bar. O is a stud. P is an extension or bracket of the secondary feed-lever. R is an adjustable stitch or feed regulating lever. S is a slot in the 35 stitch-regulating lever. T is a crank-pin secured to a shaft, T', which projects from a milled-headed thumb-nut, T², that is journaled in the bed B, as more fully described in Letters Patent granted to me October 10, 1882, No. 265,686. U is a feed-bar. V is a feed-spring. X is a shuttle-carrier. Y is a driving balance-wheel. r is a lip on the lever R.

40 Motion being given to the main needle-driving shaft A², the eccentrics B' B² give a reciprocating motion to the pitman C and pitman-lever D D'. The bell-crank lever E being connected to the shuttle-lever G by the ball M,

fitting into a fork in the rear end of the lever G in the usual way, the shuttle receives the requisite motion. The pitman-lever D D' is 55 slotted and works on the pin g, and it being connected to the main feed-lever K by the ball-and-socket joint N an up-and-down forward-and-back motion is imparted to its front end, K'. The up-and-down motion is imparted to 60 the feed-bar U, and the forward-and-back motion to the secondary feed-lever L, the spring V performing the usual function of keeping the feed-bar and lever L in contact with the end of the feed-lever K'. The length of stitch 65 is regulated by moving the feed-regulating lever R to or from the stud or pivot O of the secondary feed-lever L. This movement of the lever R is effected by turning the milled thumb-nut T², which is fixed to the shaft T'. The crank-pin T, fixed to the shaft T', engages in the slot S, and moves the lever R to the desired position 70 on the regulating-lever L. The lever R has a lip, r, which engages with the lever L to receive motion, which is more or less as the lip 75 r engages with the lever L near to or remote from the fulcrum or pivot O.

In the construction shown the spring V is used to keep the lever L in contact with the lever K K'; but it will be readily understood 80 that the extension or bracket P may be slotted and the lever K K', which has a positive motion, may engage the said slot in the bracket-extension, and thus impart a positive motion 85 to the lever L, and the spring V be dispensed with. Or, instead of slotting the bracket P, the lever K K' may be slotted so that said lever may embrace a pin on said bracket, and also by slotting the feed-bar U longitudinally 90 positive motion may be imparted to all the feeding devices without the use of the spring V, so that without any change in the secondary feed-lever or in the means of adjustment, and by the employment of any of the common means for giving the main feed-lever K K' 95 horizontal movements only, and with any usual means for giving the feed-bar positive up-and-down movement, positive feed mechanism adapted to be adjusted to regulate the length 100 of the stitch is provided.

It will be also readily understood that instead of the eccentric B' and its strap a slotted yoke or yokes and one or more cams of any desirable form may be substituted.

A radius-bar and pin may be used instead of the slot and pin *g* as a fulcrum for the pitman-lever *D D'*, and other changes within the province of mechanical skill may be made without departing from the spirit of my invention.

Having fully described my invention, I claim—

1. The combination, with the main shaft, of a main feed-lever, mechanism for operating said main feed-lever from said shaft, a secondary feed-lever connected to said main feed-lever, a feed-bar, a feed-regulating lever pivotally secured to said feed-bar, and means for adjusting said feed-regulating lever relative to said secondary feed-lever, substantially as set forth.

2. The combination, with the main shaft, of a feed-bar, a main feed-lever connected with said feed-bar and adapted to lift the same, mechanism for operating said main feed-lever from said main shaft, a secondary lever connected to said main feed-lever, a feed-regulating device, and means for adjusting said feed-regulating device relative to said secondary lever, substantially as specified.

3. The combination of the main shaft, an eccentric thereon, a pitman-lever, a main feed-lever, a secondary feed-lever, a feed-bar, a feed-regulating lever pivotally secured to said feed-bar, and means for adjusting said feed-regulating lever, as set forth.

4. The combination of the main shaft *A²*, eccentric *B'*, pitman-lever *D D'*, main feed-lever *K K'*, secondary feed-lever *L*, feed-regulating lever *R*, and means for adjusting said lever *R* at the will of the operator, substantially as set forth.

5. The combination of the main shaft and its eccentric, the pitman-lever *D D'*, the levers *K K' L R*, and feed-bar *U*, substantially as set forth.

6. The combination of the main shaft and eccentrics *B' B²*, pitman *C*, levers *E* and *G*, pitman-lever *D D'*, the levers *K K' L R*, and feed-bar *U*, substantially as specified.

THOS. A. MACAULAY.
